UNITED STATES PATENT OFFICE.

ELVIN COLLINS AND MARK HEARN, OF MAITLAND, COLORADO.

MOTOR-DRIVEN HAND-TOOL.

No. 852,258.

Specification of Letters Patent.

Patented April 30, 1907.

Application filed June 20, 1905. Serial No. 286,194.

To all whom it may concern:

Be it known that we, ELVIN COLLINS and MARK HEARN, citizens of the United States, and residents of Maitland, in the county of Huerfano and State of Colorado, have invented a new and Improved Motor-Driven Hand-Tool, of which the following is a full, clear, and exact description.

Our invention relates to motor driven hand tools, but more particularly to a type of hand tool operated by means of an electric motor and capable of serving various useful purposes, such as that of a hand saw, a grind stone, an emery wheel, or the like.

Reference is to be had to the accompanying drawings, forming a part of this specification, in which similar characters of reference indicate corresponding parts in all the figures.

Figure 1 is a perspective view showing our invention in use; and Fig. 2 is a fragmentary side elevation of the motor mechanism, a grind stone being substituted for the saw.

The motor is shown at 3 and is provided with a handle 4 whereby it may be manipulated somewhat after the manner of a hand saw. An eye 5 is connected rigidly with the motor, and secured to this eye is a cord 6 which passes over pulleys 7, 8 and is connected with a counterweight 9 which balances the motor 3. The saw is shown at 10 and is mounted rigidly upon the armature shaft 12 of the motor 3. If desired, instead of the saw 10 a grind-stone 11, or any analogous revoluble member, such as a brush wheel or an emery wheel, may be substituted. The electric wires 13, 14 are used for energizing the motor in the usual manner.

Our invention is used as follows:—The motor 3 being energized in the usual manner, the operator grasps the handle 4 and so manipulates it as to press the saw 10 into engagement with the part to be operated upon. For instance, if the device is used in a butcher shop, the saw 10 is at the proper moment pressed into engagement with the bone to be sawed, the revolution of the saw making the cut, while the handle 4 is manipu-

lated merely for the purpose of guiding the saw. The operator does not sustain the weight of the motor, or of any part thereof, for the reason that the same is supported by the counterweight 9. The operator can move the motor upward or downward at will.

In Fig. 2 a grind stone 11 takes the place of the saw 10. This grind-stone may be used for any purpose, for instance, for sharpening any edged tool or for dressing any surface usually treated by the rotation of a grind-stone.

We do not limit ourselves to any particular type of revoluble tool to be mounted upon the armature shaft 12. Neither do we limit ourselves to the particular means shown for balancing the motor, nor for guiding the revoluble tool.

Having thus described our invention, we claim as new and desire to secure by Letters Patent:—

A motor driven hand tool comprising an anti-friction support, a cable arranged on said support and having end portions depending from the same, an electric motor having a casing connected to and depending from one end portion of the cable and also having a horizontal armature shaft journaled in and extending laterally from said casing, a vertically-disposed, rotating tool fixed on the extended portion of the armature shaft and arranged at one side of the casing, a handle fixed to and extending rearward from the casing and arranged in a plane parallel to that of the rotating tool, and a counterweight connected to the other end portion of the cable and balancing the motor casing and the parts carried thereby.

In testimony whereof we have signed our names to this specification in the presence of two subscribing witnesses.

ELVIN COLLINS.
MARK HEARN.
